UNITED STATES PATENT OFFICE.

GEORGE HENRY RYPER, OF LONDON, ENGLAND.

STAMPING MACHINE.

Application filed May 2, 1927, Serial No. 128,281, and in Great Britain May 6, 1926.

This invention relates to automatic stamping machines adapted to moisten, detach and affix a postage or like stamp from a strip.

Automatic stamping machines have already been proposed in which the moisture is applied to the envelope, card, or other device to which the stamp is affixed, and machines have also been proposed in which the stamps are moistened by being drawn over a roller before separation from the strip.

The latter type of apparatus suffers from the disadvantage that the stamp tends to move faster than the roller, producing a wiping or rubbing movement of the gummed surface which tends to remove the adhesive and also to moisten part or the whole of the next stamp which may not be required for immediate use.

The present invention has for its object to provide a machine of the above type in which moisture is applied only to the stamp next about to be affixed by means of a pad applied to the gummed surface with an approaching as opposed to a wiping movement. The approaching movement is preferably approximately at right angles to the surface of the stamp but it may be oblique thereto or along a curved line, the essential feature being that the pad contacts with the stamp with a "dab" or light blow in which there is no substantial rubbing or wiping of one surface across the other in the common plane of the surfaces.

The invention also comprises an improved moistening device and an improved general construction of machine as will be herein-after more fully described and set out in the appended claims.

The invention is illustrated in the accompanying drawing in which

Fig. 1 shows an end view.

Fig. 2 shows a plan with the cover removed.

Fig. 3 is an elevation of the internal mechanism illustrated in Fig. 2, the front wall being removed.

Fig. 4 is a sectional elevation on the line IV-IV of Fig. 2, and

Fig. 5 is a view of a detail in perspective.

Turning now to the drawing, the improved machine according to the invention comprises a casing 1 surmounted by a cover 2 and housing at its upper part a shaft 3

carrying cams 4, 5, 6, Fig. 2, by which the various mechanisms are actuated. The shaft 3 is adapted to be rotated by a toothed wheel 6^a actuated by a sector 7 carried by a hinged arm 8 having a handle 9. The toothed wheel drives the shaft in one direction only by any suitable form of free-wheel clutch. The cam 4 is shown in dotted lines in Fig. 1 and is adapted to actuate through a lever 10 a shaft 11 to which a cranked lever 12, Fig. 3, is rigidly fixed. The lever 10 is held on to the cam by a spring 10^a.

Cam 6, Fig. 3, actuates a rectilinear lever 13, Fig. 3, loosely mounted on shaft 11 and carrying at its free end a pivoted arm 14, the lower end of which carries a plate 15 supporting a damping rod 16. The lever is held on to the cam by a spring 13^a and the arm 14 is connected to the cranked lever 12 by a pivoted link 17. An extension 13^a of lever 13 extends forwardly of the casing for a purpose that will later appear.

The lower end of the cranked lever 12 is connected by means of a pivoted link 18 to an arm 19 connected to one element of a free-wheel clutch which may be of any suitable form, but is shown in Fig. 3 as comprising rollers mounted in peripheral grooves of one element of the clutch, the other element of which comprises the feed roller 20 for the strip of stamps 21 normally housed in container 22 which is removable when required from the apparatus.

Turning now to Figs. 2 and 4, cam 5 operates the double rectilinear levers 30 and bell crank lever 31 all loosely mounted on shaft 11. The levers 30 engage an affixing plunger 32 slidable in a housing in the front part of the casing, the lower flat face of the plunger being perforated as shown at 33 and normally positioned just above the slot 34 through which the strip 21 emerges from the casing. The affixing plunger 32 is hollow and houses a suction-producing plunger 35 comprising a metallic piston-like member at its lower end surmounted by a cup leather 36.

Forwardly of the plunger housing is mounted a detachable water receptacle 37 positioned in the housing 38 of which the lower end is closed by an absorbent pad 39. The water receptacle is provided with a chamber 39^a in which water can penetrate through a plug 40 having a groove regis-

tering with a hole 41 in the wall of chamber 39^a and right angled passages communicating between said groove and the end face of the plug, the outlet to said passages being controlled by a ball valve 42. The chamber also communicates with a central pump chamber 43, the lower end of which is closed by a ball valve 44. The pump piston 45 working in chamber 43 is operated at each stroke of lever 13 by extension 13^a to depress the pump piston 45 causing any water received into the chamber 43 to drop past valve 44 on to the pad 39, the piston being returned by its spring 45^a and in its upward stroke withdrawing the valve 42 from the plug opening so that a small quantity of water again passes from chamber 37 into the chamber 39^a. In this manner the pad 39 is maintained continually supplied with water and by slightly screwing in or out the plug 40, the amount of water supplied at each stroke of lever 13 can be accurately controlled.

The roll of stamps is normally housed in a removable chamber 51 shown separately in Fig. 5 and comprising two hinged parts provided with extensions or lips 52, 53 lying one above the other to form guides for the strip. The lips are cut away at the point 54 so that the feeding roller 20, Fig. 3, can engage through the slot so formed to engage with the paper.

In conjunction with this roller I provide a second roller 55 carried at the end of a hinged arm 56 adapted to be rocked on a spindle 61. The arm is controlled by a spring 57 and engaged by means of a cam 58 operable by a knob positioned outside the casing to raise and lower the roller 55 from engagement with the upper surface of the strip. The feed roller 20 is also capable of being operated from a knob positioned outside the casing to feed forward the strip after the container has been inserted in position.

It will be observed that all the levers hitherto described are in their operative movements actuated by springs against the low parts of the cam. With the present arrangements, however, a convenient method of controlling the amount of feed of the strip at each operation of the device, comprises a cam 60 rotatable on shaft 61 and adapted to be operated by means of a screwed collar to limit the movement of lever 19 under the action of spring 10^a to each operation of the device.

The letter, card, or other object required to receive the stamp is held on a table 70 supported by hinged parallel links 71, 72 and maintained in its uppermost position by means of a spring. The exact setting of the height of the table can be adjusted by raising or lowering the rod 74 in slots 74^a in the casing.

The operation of the device as hitherto described is as follows:-

On drawing down the handle 9, the shaft 3 is given one complete revolution. During this movement, cam 6 first acts to rock lever 13 lowering pad 16 from contact with pad 39. At the same time cam 4 allows lever 10 to rock in a counterclockwise sense in Fig. 1, so that arm 14 is brought to the position shown in dotted lines in Fig. 3, this movement being effected by the rocking of lever 12 with arm 10 and through connecting link 17. In this position, the roller at the end of lever 13 falls into the lower part 6^c of cam 6 so that the damping pad 16 is raised to moisten the lower surface of the end stamp of strip 21 beneath the lower face of plunger 33. It will be appreciated that this movement in the form shown is purely an approaching movement so that the pad 85 applies a "dab" or light blow to the surface of the stamp which does not tend to wipe away any of the adhesive and also ensures that moisture is only applied to the stamp next requiring to be affixed.

During the application of the pad to the stamp, cam 5 commences to lift suction piston 36 which applies suction through the holes 33 to the upper face of the stamp and prevents its dislodgment when pad 16 moves away. The stroke of piston 36 continues whilst pad 16 is stationary. Pad 16 then moves down as the end of arm 13 reaches the high part of the cam 6^b and immediately afterwards the high part of cam 4 moves lever 10 in a clockwise sense in Fig. 1 causing the crank lever 12 to restore arm 14 to its extreme position. Pad 16 is then moved into contact with pad 39 for a fresh charge of moisture.

When pad 16 has moved clear of the stamp, the cam 5 begins to rock lever 30 causing affixing plunger 32 to descend shearing off the stamp from the edge of the strip against a shearing plate 80 mounted on the front of the casing and affixing the stamp to the letter, card, or other object placed on table 70.

It will be appreciated that the descent of the affixing plunger 32 continues the production of suction through the holes 33 during the shearing process, so that the stamp remains flat beneath the face of the affixing plunger to ensure its proper positioning on the letter.

The construction of the suction plunger is of some importance as it is desirable for best results that the plunger should abut close against the inner face of the bottom wall 33 of affixing plunger 32 so that no air remains within the latter before the suction plunger begins to move. At the same time a tight joint between the two plungers is effectively provided by cup leather 36.

It will be appreciated that by this ma- 130

chine, I provide a damping device the size of which can be exactly determined according to the size of the stamp and which therefore only moistens the end stamp of the strip next about to be affixed.

It will further be appreciated that the damping pad is not applied with a wiping movement, but is applied with a direct pressure moving on to or off the gummed surface of the stamp with a movement more or less at right angles thereto, the face of the pad remaining parallel to the surface of the stamp during this movement.

I claim:

1. In a stamping machine adapted to moisten, detach and affix a stamp having an adhesive surface from a strip of such stamps, moistening means comprising a flat pad, a lever carrying said pad, a pad-moistening device, lever-operating mechanism adapted to operate said lever to carry said pad downwardly from said pad-moistening device, laterally to face the said adhesive surface of said stamp and upwardly against the said surface.

2. In a stamping machine adapted to moisten, detach and affix a stamp having an adhesive surface from a strip of such stamps, moistening means comprising a flat pad, a lever carrying said pad, a pad-moistening device, an operating shaft, cams mounted in said shaft, said cams being arranged during each operation of said shaft to operate said lever to carry said pad downwardly from said pad-moistening device, laterally to face the said adhesive surface of said stamp and upwardly against the said surface, and then to return said pad to initial position.

3. In a stamp applying machine, an affixing plunger for applying the stamp, means for feeding the stamp in line with the plunger, means for holding the stamp in contact with the plunger, and means operative from below the stamp for applying moisture to

the stamp, while the stamp is held in contact with the plunger, said moisture applying means moving directly toward and from the stamp to avoid a relative wiping movement.

50

4. In a stamp applying machine, a stamp affixing plunger movable vertically to apply the stamp, means for feeding a strip of stamps to position a stamp in a line with the plunger, suction means operating within the plunger to hold the stamp in contact with the operative end of the plunger, and a moistening element movable to a position below the stamp and thereafter actuated to move directly toward and into contact with the stamp to moisten the same without a relative wiping movement.

55

5. In a stamp affixing machine, a plunger, means for operating the plunger vertically for stamp affixing purposes, a suction means operative within the plunger to hold the stamp to the plunger, a stamp moistening element, means located beyond the plunger for moistening said element, and means for swinging the element from the moistening means to a position in line with and below the stamp, said means operating thereafter to move the element directly toward and in contact with the stamp to moisten the same.

60

6. In a stamp affixing machine, a stamp applying plunger movable from a stamp receiving position to a stamp applying position, suction means to hold a stamp to the plunger during operation of the plunger, means for feeding a stamp into line with the plunger, stamp moistening means operative from below the plunger and movable directly toward and from the same to moisten the same by non-wiping contact, and a plural cam shaft for operating the plunger, suction means and moistener in selected sequence.

75

In testimony whereof, I affix my signature.

GEORGE HENRY RYPER.
